UNITED STATES PATENT OFFICE.

GEORGE C. WEBSTER, OF HALIFAX, NOVA SCOTIA, CANADA.

SEPARATOR.

Application filed February 17, 1925. Serial No. 9,845.

This invention relates to an improvement in separators, and has for its object to provide a separator which is especially designed and adapted for use in separating pulverulent, powdered, or finely comminuted solids from air laden therewith.

A further object is to provide a separator having the foregoing enumerated advantages and capacities and which also effects a complete and thorough separation in an efficient, safe and clean manner by means of instrumentalities simple and durable in construction, reliable in operation, and easy and comparatively inexpensive to manufacture and operate.

Other objects and advantages will be apparent during the course of the following description taken in conjunction with the accompanying drawings, in which:

20 Figure 1 is a view partly in elevation and partly in section showing one embodiment of the invention,

25 Figure 2 is a view in section on the line 2-2 of Figure 1, parts being shown in elevation for the sake of illustration.

Figure 3 is a view in section on the line 3-3 of Figure 2, parts being shown in elevation for the sake of illustration.

30 Figure 4 is a fragmentary detail view partly in section and partly in elevation showing the automatically operable valve of the dust collector.

Referring to the drawings the numeral 10 designates a building structure in which a separator, designated generally at 11, is located. The separator 11 includes a base 12 on which an electric motor 13 is supported. The motor 13 operates a suction or exhaust fan 14. The suction or exhaust fan 14 includes a casing 15 in which a fan proper, designated at 16, operates. The inlet to the fan casing 15 connects with an offtake 17 of a chute 18, the offtake leading into the underside of the chute adjacent its lower end. 40 The chute 18 is inclined and its upper open end is connected with the lower open end of an hopper 19, the hopper 19 being supported on the chute and on a standard 20. Within the chute 18 an inclined screen or sieve 21 is positioned and suitably secured.

45 The exhaust or discharge port of the fan casing 15 connects with a conduit 22 which leads to a dust collector, designated generally at 23, and which constitutes this invention, and is preferably located exteriorly of the building structure.

The dust collector 23 includes a cylindrical outer casing 24 having its ends closed by end plates 25 formed with square openings 25^a. Of course, it is to be understood that the configuration of the openings of the end plates may be varied. An inner casing 26 is set in the outer casing and the inner casing is of square form and preferably corresponds in form and size to the shape of the openings 25^a. 60 The inner casing 26 includes vertical side walls 27 and horizontal top and bottom walls 28. The top and bottom walls 28 are provided with flanged ports or openings 29, the openings or ports of the top wall being in a vertical line with the opening or ports of the bottom wall and the aligned openings of the ports being connected by cylinders 30 of fabric or other material which is pervious to air but impervious to dust. An imperforate shield 31 covers the top wall 28. The conduit 22 is provided with a portion 22^a which constitutes the inlet to the collector 23 and which delivers the dust-laden air to the casing 24 substantially tangentially thereof. As shown 70 to advantage in Figure 3 a separating chamber 32 is formed in the casing 24 and around in this chamber 32 the dust-laden air whirls and this whirling motion tends to precipitate the dust in the air. The air after whirling around from the top of the chamber 32 to the bottom thereof passes up through the flanged openings 29 in the bottom wall 28 of the inner casing 26 into the filtering sleeves 30. 75 The air passes through the sleeves 30 to the atmosphere but the dust cannot pass through the sleeves and falls down into the lower portion of the casing 24. Should any dust pass up through the upper ends of the tubes it will impinge the shield 31 which is dome-shaped and which will return the dust through the tubes 30. The lower portion of the casing 24 is formed with a hopper 33 terminating in a discharge portion 34 of cylindrical form. A conical valve 35 co-acts with the discharge portion 34 and is carried on an angular arm 36 pivoted, as at 38', on the bracket 38 and controlled by an adjustable weight 39. The weight 39 operates to hold the valve 35 closed until the hopper is about 80 two-thirds full when the weight of the dust pushes the valve 35 downwardly to permit the dust to fall from the outlet 34. This escape of the dust continues until the hopper is about one-fourth full when the force exerted by the weight 39 will be sufficient to 85 close the valve. The discharge outlet 34 is 90

95

100

105

110

always blocked by some dust and consequently escape of the air through the outlet is prevented.

The dust which falls from the outlet 34 passes into a hopper 40 formed on the upper end of a flaring cover 41 provided for a dust receptacle 42. A fabric envelope 43 may be secured to the discharge outlet 34 by means of a clamp 45 and hangs down over the hopper 40 and cover 41 to preclude any possibility of the escape of dust. As shown in Fig. 4 the outlet 34 extends down into the hopper 40 so that in some instances it may not be necessary to employ the envelope 43.

15 The collector 23 may be supported in any suitable manner and in the construction shown the collector is formed with a pair of eyes 50 slidably fitted on a supporting rod 51 carried by one or more posts 52.

20 With the arrangement described herein admixed large particles and finely comminuted solids, such, for instance, as a mixture of ashes, cinders and partially burned and relatively large pieces of coal, is dumped into the hopper 19, the electric motor having been started and the butterfly valve 60 having been opened. The mixture slides over the screen or sieve 21 and during its passage down the screen the suction exerted by the exhaust fan draws the ashes or finely comminuted solids through the screen, through the offtake 17 and into the fan casing and expels the dust thus entrained through the conduit 22 to the collector 23 wherein the dust is separated from the air as hereinabove described.

25 The solid or relatively large particles, such as cinders, or the like, drop out of the lower end of the chute into the receptacle 61.

It is proposed to use the structure hereinabove described in many and various ways and for this purpose an auxiliary inlet 65 is provided into the offtake 17 of the chute 18.

Any desirable type of cleaning or sifting tool may be coupled up to the auxiliary inlet 65 by any suitable means.

I claim:

1. A dust collector for separating finely divided entrained particles from an air current comprising an outer casing having end

plates provided with openings, an inner 50 casing of tubular form set in the outer casing and spaced therefrom and having its open ends registering with the openings in the end plates, filtering tubes carried by the inner casing communicating with the space between 55 the inner and outer casing, said filtering tubes permitting the escape of air but preventing the escape of dust, and an inlet for dust laden air opening into the space between said casings.

2. A dust collector for separating finely divided entrained particles from an air current and comprising an outer casing having end plates provided with openings, an inner 60 casing of tubular form set in the outer casing and spaced therefrom and having its open ends registering with the open ends of the end plates, a dust laden air inlet opening into the space between said casing, filtering tubes carried by the inner casing communicating 65 with the space between the inner and outer casing, said filtering tubes permitting the escape of air but preventing the escape of dust, said outer casing having a dust discharge equipped with means to prevent the 70 passage of air therefrom.

3. A dust collector for separating finely divided entrained particles from an air current and comprising an outer casing having end plates provided with openings, an inner 75 casing of tubular form set in the outer casing and spaced therefrom and having its open ends registering with the openings in the end plates, an inlet for dust laden air opening into the space between said casings, filtering tubes carried by the inner casing and opening through the top and bottom walls thereof and communicating with the space between the inner and outer casing, said filtering tubes permitting the escape of air but preventing the escape of dust, an imperforate shield located over the upper end of said inner casing and adapted to return the dust passing through the upper ends of the tubes back 80 through the tubes into the outer casing, and means for conducting the collected dust from the outer casing.

GEORGE C. WEBSTER.
